ATTORNEY.

UNITED STATES PATENT OFFICE.

LEWIS S. WHITING, OF ASHLAND, ASSIGNOR OF ONE-HALF TO HORACE H. WHITING, OF CANTON, OHIO.

CLOVER-HULLER.

SPECIFICATION forming part of Letters Patent No. 447,743, dated March 3, 1891.

Application filed June 5, 1890. Serial No. 354,398. (No model.)

To all whom it may concern:

Be it known that I, LEWIS S. WHITING, a citizen of the United States, and a resident of Ashland, county of Ashland, State of Ohio, 5 have invented a new and useful Improvement in Clover-Hullers, of which the following is a full, clear, and exact description, reference being had to the accompanying drawings, making part of this specification.

10 My invention relates to clover-hullers; and it has for its object to provide a support for the hulling-cylinder and means by which quick and easy access may be gained to the cylinder for the purpose of repairing the same, 15 as well as for the removal of obstructions.

With these ends in view my invention consists in certain features of construction and combination of parts, as will be hereinafter described, and pointed out in the claims.

20 Figure 1 is a vertical longitudinal view through the front portion of the frame and a transverse section of the thrashing and hulling cylinders, showing the relative position of these parts in the frame. Fig. 2 is an end 25 view of the hulling-cylinder frame and concave. Fig. 3 is a sectional view through the cylinder and concave-supporting hinge.

As my invention is applicable to many of the clover-hullers now in use and well known 30 to the builders and users of such machines, I will proceed with a description of my invention, referring to the frame, thrashing-cylinder, and other parts only as conjunctional thereto.

35 A represents the thrashing-cylinder, by which the seed-balls are thrashed from the straw, after which by well-known appliances the seed-balls are conveyed to the hulling-cylinder. This description will serve to call attention to the location of the two cylinders, 40 the hulling-cylinder being below and to the rear of the thrashing-cylinder.

C represents the machine-frame, which is the common support of the several parts of 45 the machine, having the girder C', to which is bolted a cast-metal plate a, having at its lower front corner a depending portion a⁹, in which is placed the cross-shaft D, on which the front side of the hulling-cylinder frame 50 is hinged, as will be hereinafter described.

The cylinder-supporting frame E is composed of the cast metal end pieces a¹⁰, having an outwardly-projecting flanged portion a² to form a support for the cylinder-shaft journal-box a³, and an arm portion a⁴, having a perforation a⁵ to receive the supporting-shaft D, and an outwardly-projecting flanged portion a⁶, to which the ends of the concave staves F are secured by the bolts a⁷, thus forming a rigid frame, in which the hulling-cylinder B 60 is supported.

To provide for opening the concave, the front staves a⁸ have integral arms a⁹ to receive the end portion b of the shaft D, about which it hinges. The end piece a¹⁰ is provided with 65 lugs b', between which is pivotally secured an eyebolt b², the lower or free end of which swings into a notch b³ in the end of the stave a⁸, and the nut b⁴ is turned up against the 70 stave to hold it in position.

On the side plate a there are provided lugs b⁵ and on the end piece a¹⁰ of the cylinder-frame corresponding lugs b⁶. Between the former is pivotally secured an eyebolt b⁷, that will swing between the lugs b⁶ when the cylinder-frame is in normal position, the nut b⁸ to take under the lugs b⁶ to hold the frame and cylinder in operative position. When arranged as hereinbefore described, by loosening the nuts b³ the eyebolt may be swung out 80 from the lugs b⁶ and the cylinder-frame and cylinder dropped down, as shown in Fig. 2, exposing the upper portion of the cylinder for the purpose of repair, and to open the concave the nut b⁴ is turned back a distance, the 85 end of the eyebolt b² swung out from the notch in the stave a⁸, and the stave released to swing down and out about the shaft D, thus forming an opening into the concave and the front lower part of the cylinder for the purpose of 90 repair or for the removal of obstructions.

Having thus fully described the nature and object of my invention, what I claim as new, and desire to secure by Letters Patent, is—

1. In a clover-huller, the concave consisting 95 of end pieces a¹⁰, staves F, means for securing them to the end pieces, a concave stave a⁸, having a hinged connection with the machine with one and removably secured with the other end to the body of the concave, in com- 100

bination with means for securing said concave in operative position to the machine, substantially as set forth.

2. In a clover-huller, the concave consisting
5 of end pieces a^{10} , staves F, means for securing
them to the end pieces, a concave stave a^8 ,
having a hinged connection with the machine,
and an eyebolt pivotally secured to the end
piece a^{10} and having its free end adapted to
10 engage the concave stave, in combination

with means for securing said concave in op-
erative position to the machine, substantially
as set forth.

In testimony whereof I have hereunto set
my hand this 26th day of May, A. D. 1890.

LEWIS S. WHITING.
